COMBINATION DAY BED AND DAVENPORT

Filed March 6, 1930

Fig. 3. 9 1/11 8 '12 Inventor
Philip H. HASSER

By His Attorney *John J. Lynch*

UNITED STATES PATENT OFFICE

PHILIP HACKER, OF BROOKLYN, NEW YORK

COMBINATION DAY BED AND DAVENPORT

Application filed March 6, 1930. Serial No. 433,641.

This invention relates to a combination day bed and davenport and in particular to removable frames thereof and general construction which may be used with either a settee, day bed or lounge of general folding character.

A particular object of my invention is to provide a simplified mechanism which is compact and which operates with ease so that a minimum of effort is required in opening and closing the device.

A still further object of my invention is to provide a plurality of frames, one of which moves vertically and the other of which swings to a position above the vertical moving frame when the same has been lowered automatically by the swinging movement of the swinging frame, there being a space provided between them for the storage of bed clothing, pillows and the like.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

Figure 1 is a view in end elevation of a combination day bed and davenport constructed in accordance with my invention and being shown in its open or davenport position.

Figure 2 is a fragmentary view of one end of the construction as illustrated in Figure 1, both ends of the combination day bed and davenport being substantially identical in construction.

Figure 3 is a view similar to Figure 1 showing the combination day bed and davenport in its folded or closed position.

Figure 4 is a view in elevation of an end piece that may be employed in combination with the day bed or davenport and which is provided with key members that are arranged to engage suitable key plates on the bed construction, and

Figure 5 is an enlarged section taken on

the line 5—5 of Figure 4 showing the construction of the key member that is employed in securing the end pieces of the combination day bed and davenport to the frame.

Referring to the drawing in detail, 5 indicates the main or stationary frame which consists of the side corner pieces 6 to which are secured in any suitable manner the ends of the side boards 7, these side boards serving to enclose the major portion of the frame so that the mechanism and springs of the various parts of the bed are concealed when the same is used as a day bed. The frame 5 further consists of the bottom strips or angle members 8 to which are pivoted the operating arms of the vertical movable frame.

Inasmuch as both ends of the construction are identical, it is presumed that a description of one end thereof will suffice and accordingly, one end of the construction will be explained in detail, it being understood that the frame 5 is used at the opposite ends of the construction and is joined by the side boards 7 to make a rigid base or fixed frame in which the other frames operate.

Within the fixed frame 8, there is provided a toggle arm 9, whose vertically positioned end 10 is pivoted to the upper and lower toggle links 11 and 12 respectively. The upper toggle link is connected to the vertically movable frame 13 and the lower toggle link is connected through the medium of a bracket 14 with the frame 5. The vertical movable frame 13 is arranged to support an upper spring 15 upon which is mounted the mattress 16 and has suspended therefrom, the lower spring frame 17 through the medium of the angles 18. The lower spring frame 17 is arranged to support the lower ends of the springs 18—A to which they are secured.

One end of the vertical movable frame 13 is slotted as at 19 and houses a spring 20 which is secured at one end in the vertically movable frame as at 21 and at its opposite end is connected to the toggle operating lever 22 which is pivoted as at 23 to the fixed frame piece 8, the toggle arm 9 being secured thereto as is the toggle strip 24 which is also connected to the vertically movable frame 13.

The toggle operating lever 22 is provided

with the offset finger piece 25 which is arranged to be engaged by the pivot arm 26, which, in turn, is pivoted to the vertical member 6 of the stationary frame 5. The outer end of the pivot arm 26 has secured thereto, the upper end of the leg 27 which supports the swinging frame of the bed construction in its proper spaced relation with the floor. The leg 27 is pivoted as at 28 to the swinging frame 29 which, in turn, through the medium of the springs 30, supports the mattress holding frame 31 and 32 upon which the mattresses 33 and 34 are respectively mounted. The swinging frame 29 through the medium of the hinge pieces 35 and 36 is movable into the position illustrated in Figure 3 and during its swinging movement the pivot arm 26 revolves about its point of pivotal connection with the frame 5 and engaging the finger 22, forces the toggle operating lever 22 to the right, as illustrated in Figure 1, until the toggle arm and link 12 and 24 permit the lowering of the vertically movable frame into the position illustrated in Figure 3.

The upper end of the arm 22 and the leg 27 are connected through the medium of the foldable links 37 and the pivot pin 38 which joins one of the foldable links with the leg 27, also connects the pivot arm 26 with the leg 27 and there is mounted on said pivot pin 38, the spring arm 39 to which is secured the coil spring 40. The opposite end of the coil spring being secured to the hinge piece 35, this spring serving to hold the leg 27 when the swinging movement of the frame 29 takes place so that all of the levers are folded compactly and the springs 40 and 20 assist in the closing operation of the bed and hold the parts in their proper relation so that rattling and other noises due to the loosely pivoted legs, toggles and links, is prevented.

The side members of the frame 5 are provided with key plates 41 having openings therein for the reception of key members 42 which are carried on the bed end pieces 43. It is understood that any type of end piece may be employed, that is, the end pieces may be arms for a sofa or davenport construction and the bed frame is set down into the end pieces and rests on the key members so that the bottom of the frame is in spaced relation with the floor.

In use as a day bed, the wooden sides 7 of the frame 5 provide a finished construction and enhance the appearance of my combination day bed and davenport.

It is quite evident that when the device is open, it serves as a bed for two people and when not in use, it is folded so that the mattress 34 of the swinging frame is on top and the vertical movable frame 13 has been lowered into the frame 5 and the swinging frame 29 positioned thereover to leave a space 44 in which may be stored pillows, bedding or the like.

In the operation of my device, the frame 13 is raised by the upward movement of the arm 22 through the medium of the toggle levers 11 and 12 and toggle arm 9, the upward and outward pull on the lever 22 being occasioned by the links 37 when the upper or 70 swinging frame 29 is pulled upwardly and outwardly, the movement of the lever 22 being limited by the foot 25 and the frame 29 being accordingly supported by the leg 27. The folding movement of the frame 29 is permitted through the medium of the hinge pieces 35, one of which is secured to the bed frame 6. When the bed is to be closed, the frame 29 is lifted upwardly and hinges about its pivot point and the lever 22 folds down carrying with it the toggle arm 9 which breaks the supporting standard formed by the toggle arms 11 and 12 and permits the folding down movement of the frame 13 into the position illustrated in Figure 3. The 85 frame 29 will, when it is turned about its pivot point, have its under side uppermost and this turning movement will fold the leg 27, links 37 and arm 26 down alongside the 90 bed construction when it is folded into its frame 6.

It is evident, therefore, that I have provided a combination day bed and davenport in which the levers and links facilitate folding operation of the parts one in which a minimum amount of mechanism is employed to carry out the features of my invention.

While I have illustrated and described my invention with some degree of particularity, I realize that in practice various alterations therein may be made without departing from the spirit of the invention or the scope of the appended claims.

What I claim is:

1. In a device of the character described, a movable frame, a stationary frame, a swingable frame, spring carriers on said movable and swinging frames, a toggle arm, links joining one end of said arm to the stationary frame and movable frame, a toggle operating lever pivoted to the stationary frame and to which said toggle arm is secured, a spring in the movable frame connecting said lever with said movable frame, hinges connecting said swinging and stationary frames, a leg pivoted on the swinging frame, a pivot arm connecting the leg and the stationary frame, and an extension on the toggle operating lever for engagement by said pivot arm to 110 cause a lowering movement of the movable frame when the swinging frame is raised from the position in which it is forwardly overturned on the hinges.

2. In a device of the character described, a movable frame, a stationary frame, a swingable frame, spring carriers on said movable and swinging frames, a toggle arm, links joining one end of said arm to the stationary frame and movable frame, a toggle operating 125

lever pivoted to the stationary frame and to which said toggle arm is secured, a pin and slot connection between the movable frame and said toggle operating lever, hinges connecting said swinging and stationary frame, 5 a leg pivoted on the swinging frame, a pivot arm connecting the leg and the stationary frame, and an extension on the toggle operating lever for engagement by said pivot arm to cause a lowering movement of the movable frame when the swinging frame is raised from the position in which it is forwardly overturned on the hinges.

10 3. In a convertible sofa bed, a stationary frame, a primary bed frame, operative means by which the primary frame is mounted in the stationary frame for vertical sliding movement therein, a secondary bed frame hinged on an axis at one side of the stationary frame to rotate from a horizontal seat position over the stationary frame and above the primary frame to a horizontal bed position at one side of the stationary frame, a 15 floor engaging leg intermediately pivoted on the secondary frame, a link pivoted to the upper extremity of the supporting leg and to a second axis on the said side of the fixed frame and motion transmitting means also pivoted to the upper end of the leg and pivotally connected to said operative means whereby rotating the secondary frame on its 20 hinges from the first to the second recited position unfolds the leg to supporting position and causes the operative means to lift the primary bed frame from lowered position to a position substantially coplanar with the secondary frame.

25 4. In a day bed, a stationary frame, a movable frame including means by which the 30 frame is mounted for sliding vertically in the stationary frame, means for raising the frame, a frame hinged to the stationary frame, pivotal supports carried by said hinged frame, arms connecting pivotally the 35 supports to the stationary frame on an axis different from that of the hinged frame, and folding means connecting the means for raising the sliding frame to the arms.

40 In testimony whereof, I have signed my 45 name to this specification this 25th day of February 1930.

PHILIP HACKER. [L. s.]
